Primary Examiner — Darlington Ly*Assistant Examiner* — Jeremy Koenig(74) *Attorney, Agent, or Firm* — Barry Choobin; Patent 360(57) **CLAIM**

The ornamental design for a wheel rim, as shown and described.

DESCRIPTION

FIG. 1 is a perspective view of a wheel rim, showing our new design;

FIG. 2 is a front elevation view thereof; and,

FIG. 3 is a side elevation view thereof.

The broken lines in the drawings are for the purpose of illustrating portions of the wheel rim that form no part of the claimed design.
